RECORDING SYSTEM

John Hays Hammond, Jr., Gloucester, Mass.

Application April 6, 1933, Serial No. 664,718

12 Claims. (Cl. 179—100.4)

This invention relates to sound recording systems, and more particularly to a monitoring system for use in the recording of orchestral selections.

The invention provides means for permitting the orchestra leader or monitor to hear the music as it is being recorded, and at the same time to hear the scratch noises as they will sound when the record is being reproduced. The invention accordingly enables the leader or monitor to control the recording so that the sound level of the recorded music will at no time fall below the scratch noise level, whereby a record is produced, free from the disagreeable effect of the scratch noise which tends to predominate at times of pianissimo in the music.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawing forming a part thereof, in which the single figure illustrates diagrammatically a system embodying the present invention.

In the following description and in the claims, parts will be identified by specific names for convenience, but they are intended to be as generic in their application to similar parts as the art will permit.

Referring more particularly to the drawing, a microphone 10 is adapted to be suspended at a suitable distance in front of the orchestra or other source of sound to be recorded and is connected through a transformer 11 to the input circuit of a space discharge amplifier 12. The output circuit of the amplifier 12 includes the primary of a transformer 13, the secondary of which is connected across a potentiometer 14, the adjustable contact 15 of which is connected to the grid of a second space discharge amplifier 16. The output circuit of this amplifier 16 includes the primary of a transformer 17, the secondary of which is connected in the input circuit of a push-pull amplifier 18. The output of this amplifier 18 includes the primary of a transformer 19 which is provided with two secondary windings 19a and 19b.

The secondary 19a is connected to a phonograph engraving mechanism 21 which is provided with an engraving tool 22 for engraving a master record 23. This record is carried on the turn table 24 of a phonograph driving mechanism 25 of usual construction. The engraving mechanism 21 is mounted on the end of an arm 26,

pivoted to a shaft 27, which is slowly rotated by the phonograph driving mechanism 25, so that the engraving tool 22 cuts a spiral record groove on the upper surface of the master record 23 in well known manner.

The secondary 19b is connected across a potentiometer 31, the adjustable contact 32 of which is connected to the grid of a space discharge device 33, the output circuit of which includes the primary of a transformer 34. The secondary of the transformer 34 is connected to a pair of headphones 35, adapted to be worn by a monitor such as the director of the orchestra.

A second phonograph mechanism 41 is provided, on the turn table of which is mounted a blank record 42 which has on its upper surface a spiral groove cut by the engraving tool 22 when the engraving mechanism 21 was deenergized. Running in the spiral groove of the record 42 is the needle 43 of a phonograph pick up mechanism 44. This mechanism is connected to the input circuit of a two-stage amplifier 45 and a push-pull amplifier 46, which are similar in construction to those already described. The output circuit of the push-pull amplifier 46 includes the primary of a transformer 47, the secondary of which is connected across a potentiometer 48, the adjustable contact 49 of which is connected to the grid of a space discharge device 51. The output circuit of the space discharge device 51 includes the primary of the transformer 34.

In the operation of the form of the invention shown in the accompanying figure, the orchestra leader, for example, leads his orchestra in the usual manner. The music is picked up by the microphone 10 and amplified by the amplifiers 12, 16 and 18. The greater part of the amplified output is fed to the engraving mechanism 21, causing the engraving tool 22 to engrave a record of the music on the disc 23, which is later to be used as a master record for the production of the usual phonograph records.

A small part of the output of the push-pull amplifier 18 passes through the secondary 19b to the potentiometer 31, where any desired amount is picked up and fed to the device 33, the output of which passes through the transformer 34 to the headphones 35.

At the same time, the blank record 42 is being rotated by the mechanism 41, causing the needle 43 to run in the blank groove of the record 42. This needle then picks up the scratch and other ground noises which are amplified by the amplifiers 45 and 46, the output from which passes through the potentiometer 48 to the input circuit of the device 51. The output from this device passes through the transformer 34 where it is mixed with the output from the device 33. The combined output then passes to the headphones 35, where the orchestra leader hears not only the

music as being recorded on the disk 23, but also the scratch and ground noises of the blank record 42. The adjustable contacts 32 and 49 may be so adjusted that the relative intensities of the music 5 and scratch as heard in the headphones 35 corresponds to that in the finished record which is made from the master record 23.

In this way it is possible for the orchestra leader to hear the scratch noises together with the 10 music, so that he will not allow the level of the music produced by his orchestra to drop below the scratch and ground noise level. It is accordingly possible to make the records so that the 15 scratch and ground noise will never become objectionable, this being taken care of in the making of the records, so that no scratch eliminator will be necessary when the records are being 20 played. This system also has the advantage of allowing the orchestra leader to always hear exactly how the music will sound as it is being recorded, and in this way he can bring out certain 25 groups of instruments, the tones of which may not be amplified as much as other instruments in the orchestra. It also allows him to hear the maximum and minimum sound level of the music as recorded, so that he will not allow this to become 30 too great or too small for proper recording.

It is obvious that the headphones 35 may also be used by a monitor who controls the recording 35 in any convenient manner as, for example, by means of potentiometer 14. Furthermore the head phones are merely illustrative of any suitable sound reproducing device.

Only so much of the circuits have been shown 35 and described as is necessary to an understanding of the invention. The various details of the space discharge amplifiers, auxiliary apparatus and manner of their connection are of standard 40 form and will be apparent to a person skilled in the art.

Although one embodiment of this invention has been shown herein, it is to be understood that the invention is not limited to any specific construction, but may be embodied in various forms 45 without departing from the spirit of the invention or the scope of the appended claims.

What is claimed is:

1. The method of recording sound which comprises energizing a sound reproducing device in 50 accordance with the sound to be recorded and also supplying to said sound reproducing device energy corresponding to the normal ground noise of a record whereby said device is caused to indicate the reproducing characteristics of the record 55 being made.

2. The method of recording sound which consists in picking up, amplifying and recording said 60 sound and combining energy proportional to said sound with energy derived from the scratch noise of a sound record tablet, so that the person directing the production of said sound may hear the combined effect.

3. In a system for recording sound, a pickup 65 device for picking up sound waves, an amplifier associated therewith, a recorder for recording the output of said amplifier, a scratch producing device, an amplifier associated therewith, a mixing device for mixing the output of said scratch amplifier and part of the output of said sound amplifier and a sound indicating means operated by the output of said mixing device.

4. A sound recording system comprising a

source of sound, a means for recording said sound, a source of scratch noise, a sound reproducer, means for supplying unrecorded sound energy from said sound source to said sound reproducer and means for supplying said scratch noise to 5 said reproducer.

5. A system for recording music comprising a pick-up device for said music, an amplifier associated therewith, a sound recorder operated by the output of said amplifier for recording said 10 music on a sound record tablet, a blank sound record tablet, means associated therewith for picking up the scratch noise of said blank tablet, amplifying means associated with said last pick-up means, means for combining parts of the output 15 energy of both of said amplifying means and sound reproducing means for reproducing the combined output of said combining means.

6. A system for recording music comprising a pick-up device for said music, an amplifier associated therewith, a sound recorder operated by the output of said amplifier for recording said music on a sound record tablet, a blank sound record tablet, means associated therewith for picking up the scratch noise of said blank tablet, 20 amplifying means associated with said last pick-up means for combining parts of the output 25 energy of both of said amplifying means, means to adjust the relative intensity of the parts thus combined and sound reproducing means for reproducing the combined output of said combining 30 means.

7. A sound recording system comprising a pick-up means, a recording means, means to translate energy from said pick-up means to said recording 35 means, a blank record, means to pick up normal ground noises therefrom, a sound reproducing means and means to translate to said sound reproducing means energy from both of said pick-up 40 means.

8. A sound recording system comprising a pick-up means, a recording means, means to translate energy from said pick-up means to said recording means, a blank record, means to pick up normal ground noises therefrom, a sound reproducing 45 means, means to translate to said sound reproducing means energy from both of said pick-up means, and means to adjust the relative response of said sound reproducing means to energy from the respective pick-up means.

9. In a sound recording system, a monitoring circuit for the sound energy to be recorded and means for arbitrarily introducing ground noise into said monitoring circuit.

10. In a sound recording system, a source of sound variations, means for recording said sound variations, means for monitoring said variations and means for arbitrarily combining ground noise with part of said variations.

11. In a translating system for a sound record, 60 a source of sound variations, a pick-up device therefor, a monitoring circuit adapted to receive part of said sound variations from said device and means for arbitrarily introducing ground noise into said monitoring circuit.

12. In a translating system for use with a sound record, a source of sound energy, a source of background noise, a first and a second channel means for applying said sound energy to both of said channels and means for applying said background noise to one of said channels.
